UNITED STATES PATENT OFFICE.

JAMES D. GARVEY, OF CHICAGO, ILLINOIS.

FOUNTAIN-BRUSH.

1,194,377.

Specification of Letters Patent. Patented Aug. 15, 1916.

Application filed January 21, 1914. Serial No. 813,330.

To all whom it may concern:

Be it known that I, JAMES D. GARVEY, a citizen of the United States, and resident of Chicago, in the county of Cook and State of Illinois, have invented certain new and useful Improvements in Fountain-Brushes, of which the following is a description, reference being had to the accompanying drawing, which forms a part of my specification.

My invention relates to an improvement in fountain brushes wherein the reservoir or font may be located at a point somewhat removed from the brush proper, the construction being designed to permit of the proper feeding of the brush portion.

The object of the invention is the provision of a construction whereby the flow from the reservoir or container portion to the bristles or hair of the brush portion may be controlled by the manipulator regardless of the proximity of the manipulator to the reservoir or container portion.

The advantages inherent in the particular construction and combination will be fully understood from the specific description hereinafter given.

In the drawing:—Figure 1 illustrates, in side elevation, one form of my invention, with a portion of one of the conduits or feed tubes shown broken away. Fig. 2 is a detail sectional view of the valve mechanism. Fig. 3 is a detail sectional view of the reservoir or container and its cover-holding mechanism. Fig. 4 illustrates in side elevation a modified form of my invention. Fig. 5 is an enlarged view of a portion of the valve operating mechanism shown in Fig. 4.

In the particular exemplification of the invention, as illustrated in Fig. 1, the fountain brush comprises a suitable reservoir or container 10, which may be of any size and shape to hold the desired quantity of paint, varnish, or other fluid; the reservoir being preferably provided with a suitable cover 11 having a depending rim or flange 12, more clearly shown in Fig. 3, adapted to fit snugly into the reservoir as shown, so as to provide a comparative fluid-tight connection; the cover 11 being provided with a suitable opening as at 13 in order to induce proper flow of the fluid.

As an illustration of one form of clamping or holding mechanism for the cover 11, I show in Figs. 1 and 3 a plate or member

14 permanently secured to the side of the pail or reservoir 10 and having pivotal connection with the plate or member 15. The plate or member 15 has a bent or shoulder portion 15^a arranged to extend over the top of the cover and adapted to be readily grasped for operation. The relation between the two members 14 and 15 is controlled by the spring 16, the ends whereof are secured to the members 14 and 15 respectively, as clearly shown. The tendency of spring 16 is to draw the two members together as is clearly evident from the construction. The members or plates 14 and 15 are both provided with a cut-away portion or slot of sufficient width and length to permit the spring 16 to move from one side of the pivotal point or rather from one side of the plates or members to the other. It is clearly evident from the construction shown and described that the tendency of the spring is to pull the free member or plate 15 to either side of what may be termed the dead center, thus either holding member or plate 15 snugly on the cover or lid 11 or away from the lid when plate 15 is intended to be moved into unclamping position.

The pail or reservoir 10 may be provided with several clamping members, either diametrically or otherwise located.

In the drawing, the pail or reservoir 10 is provided with a suitable bail 17 whereby it may be carried or suspended, while the bottom is provided with suitable supports or standards 18 which may be diametrically or suitably arranged, and preferably made to extend at an angle to the sides of the pail so as to properly support the pail or reservoir and prevent tipping. The supports or standards 18 are also of sufficient length to provide a clearance beneath the pail or reservoir proper for the outlet conduit or conduits. In the illustration, the pail is preferably shown provided with a semi-spherical or concavo-convex bottom, the center whereof is provided with an outlet 19 which is preferably in the nature of a short spout or conduit extending within the pail a slight distance above the bottom so as to prevent sediment or settling discharging from the pail or reservoir. The outlet conduit, in Fig. 1, is shown provided with a coupling 20, in the nature of a four-way connection so as to receive the two oppositely disposed conduits 21, 21, and the removable plug 22,

which latter permits of the proper cleaning of the pail or reservoir and its outlet. The conduits 21 may be supported at their outer ends by suitable hangers 23, 23, in order to 5 give them proper rigidity.

The outer ends of the conduits 21 communicate with valve-casings 24, 24, either by being made integral with the valve-casings or threaded so as to screw into the threaded 10 portion 25 of the valve-casing, as shown in Fig. 2. The casing 24 is preferably in the nature of a cylinder, open at one end, in which is secured a suitable plug or member 26 which is shown threaded so as to screw 15 into the bottom of the casing 24, see Fig. 2. The plug or member 26 may be provided with a suitable wrench-engaging surface as at 26^a and a flange 26^b whereby the position of the member 26 may be determined and a 20 fluid-tight connection effected. The outer end of member 26 is shown in the nature of a frustum or tapering spout 27, and preferably provided with a groove or depression as at 27^a, which may either receive a tie- 25 wire or the reinforced end of the elastic tubing 28, so as to prevent the accidental withdrawal of the tubing.

The inner end of member 26 is formed so as to provide a suitable seat for the plug or 30 valve member 29 whereby flow through the discharge channel 30 of member 26 may be controlled. In the particular construction illustrated, the valve 29 is mounted on the end of a rod or stem 31, in any suitable 35 manner, and the rod or stem 31 made of a length sufficient to permit it to extend through the closed end of casing 24 when the valve is on its seat. The stem or rod 31 also acts as a guide to the spring 32 which 40 is secured intermediate of the valve 29 and the closed end of the casing; the ends of the spring preferably bearing on metallic plates or washers 33 and 34. In order to insure a liquid connection being effected at the upper 45 end of the casing where the stem or rod passes to the outside, I provide a suitable washer or packing 35 arranged intermediate of metallic plate 34 and the end of the casing. The outer end of rod or stem 31 is 50 arranged to receive the end of a cord or chain, which, however, may be secured by means of a suitable ring as shown at 36. To each of the rings 36, (two outlets and valves being shown in the construction illustrated 55 in Fig. 1) I secure a suitable pull-cord or chain 37, which is arranged to pass upwardly and over the small sheaves or rollers 38 mounted in the lobes or brackets 39, secured to the side near the upper end of the 60 pail or reservoir 10 and preferably in line with the point where the bail 17 is secured to the pail. The free ends of cords or chains 37 may be provided with a suitable grip or handle as indicated at 40, see Fig. 1. The 65 ends of the tubes or conduits 28 are intended

to be slipped over the tubes or hollow handles 41 of the brushes 42; it being understood that the handles 41 are provided with a suitable channel 43 extending therethrough as indicated in dotted lines in Fig. 1.

The sides of the pail or reservoir 10 may be provided with suitable holders or brackets as shown at 44, adapted to hold the handle of the brush and also the free end of the pull cord or chain 37 as very clearly 70 shown in Fig. 1 wherein one brush is shown in position for use; while the other is suspended in the bracket.

The standards or supports 18 may be reinforced by the horizontally disposed encircling member 45, which may have protruding portions or lugs as shown at 45^a, so as to maintain the conduits 28 in their encircling or wound-up position when the brush is not in use. The sides of the pail or reservoir 80 are also preferably made sloping or converging toward the bottom so as to provide proper pressure and drainage of the receptacle.

My invention is especially intended for 85 use by painters and the like; and in practice, the reservoir or pail 10 is filled with the paint or varnish which it is desired to apply, and the reservoir suspended or supported above the point of application of the 90 paint so as to induce a flow by gravity of the paint or varnish through the conduits 21 and into the valve casings 24, 24; the manipulator then operates the valve 29 by pulling the cord or chain 37 so as to raise 95 the valve sufficiently from its seat to permit the paint or varnish to flow out through spout 27 and into the flexible conduits or tubes 28, from whence it will pass through the channel 43 of the brush proper and be 100 discharged among the bristles of the brush.

It is evident from the construction that if the bristles are filled with paint or varnish faster than the manipulator can apply it, he releases cord or chain 37 so as to permit 110 spring 32 to force the valve to its seat. It is further evident that the manipulator may readily control the flow by the degree of movement of the valve; the flow through the conduits and into the brushes thus being at 115 all times within the control of the operator.

The particular construction shown in Fig. 1 permits two painters or operators to use the same reservoir or pail, each operator controlling the flow to the brush manipulated by him. A greater or less number of discharge conduits may be provided as desired, and the flow of paint, or other fluid, to the respective brushes made commensurate with the skill and speed of the manipulator.

In Figs. 4 and 5, I disclose a form of my invention, which is more especially adapted for use in stenciling and marking; the construction shown in these figures being what 125

may be more specifically termed a hand fountain brush wherein the reservoir or pail 10^a is shown of smaller dimensions and provided with a handle 46 provided with the 5 hollow vertically disposed portion 46^a which provides a suitable shield for the pull-cord or chain 37^a which is secured to the stem of the valve as in the previous construction, while the other end of the pull-cord or chain 10 37^a is secured to the rotatively mounted thumb member 47 so as to wind thereon, as more clearly shown in Fig. 5. Member 47 extends through the hollow portion 46^a of the handle and has one end thereof provided 15 with the thumb receiving portion 47^a whereby rotation of member 47 may be controlled; the other end of member 47 being held against removal by any suitable means, such as a cotter pin and the like. The construction 20 shown in Fig. 4 is provided with a single outlet conduit 21^a which connects with the valve casing 24 in a manner similar to that heretofore described. The discharge spout at the end of casing 24 receives the 25 flexible conduit 28 which fits over the tube or channeled handle of the brush 48 as shown in Fig. 4.

Where the construction shown in Fig. 4 is intended to be used, the reservoir or container 30 10^a is provided with a suitable marking fluid or other liquid, and the operator grasps the handle portion 46^a so as to permit his finger or thumb to extend through the loop 47^a of the valve-operating mechanism. By pulling 35 the thumb downwardly, in the construction as more clearly shown in Fig. 5, it is evident that chain or cord 37^a will be wound about the horizontally disposed portion of member 37 and, therefore, exert a pull on stem 31 and 40 move the valve from its seat against the action of its spring 32, thereby allowing the fluid to flow through casing 24 and into flexible conduit 28 and thence be discharged through the channel of the brush and among 45 the bristles thereof. As in the construction previously described, it is evident that the manipulator may control the flow by proper operation of the valve.

It is evident that my invention may be put 50 to various uses and that various sizes and forms of brushes may be used in connection therewith; the channels or feed tubes of the brush proper being of such cross sectional area as to provide the desired flow there- 55 through and prevent a too rapid flow onto the bristles; the flow being either continuous or intermittent as desired by the user.

I have shown and described what I believe 60 to be the simplest and best forms of my invention; it is evident, however, that certain modifications may be made without, however, departing from the spirit of my invention, and I do not wish therefore to be understood

as limiting myself to the exact constructions shown and described. 65

What I claim is:—

1. A device of the class described, comprising a pail provided with a bottom sloping toward the center thereof, an outlet at the lowermost point in said bottom, said outlet 70 comprising a tube extending into the pail a short distance above the bottom adjacent thereto, the outer or discharge-end of said tube extending to a point substantially in alignment with the pail-sides, a valve secured 75 to the outer end of said tube for controlling the flow therethrough, rotatable means adjacent the upper part of the pail-sides, flexible means secured to said rotatable means and to said valve whereby the flow-controlling 80 valve may be operated at a distance therefrom, flexible tubing secured to the discharge end of the valve, and a fountain brush secured to the opposite end of said tubing.

2. A device of the class described, comprising a reservoir provided with a bottom arranged to extend into a lower plane than the lower edges of the reservoir, the lowest point in the bottom being provided with a discharge, a laterally disposed conduit connected with said discharge, the outer end of the conduit being provided with a valve for controlling the flow through said conduit, rotative means mounted on the side of the reservoir, flexible means connected with the 95 valve and passing about said rotative means, whereby the valve may be controlled at a distance removed therefrom, flexible tubing secured to the discharge end of the valve, and a fountain brush secured at the opposite end 100 of the tubing.

3. A device of the class described, comprising a reservoir provided with a bottom arranged to extend into a lower plane than the lower edges of the reservoir, a discharge 105 tube arranged at the lowest point in said bottom and projecting into the reservoir slightly beyond said bottom, a laterally disposed conduit connected to said discharge tube and extending to opposite sides of the reservoir, 110 a spring-controlled valve secured to each end of said laterally disposed conduit for controlling the flow from said conduit, rotative means mounted on the sides of the reservoir, separate flexible means secured to each valve 115 and passing about said rotative means whereby the valves may be independently operated, fountain brushes, and flexible tubing secured to the discharge ends of said valves and to said brushes whereby the brushes may be independently supplied with fluid from said reservoir. 120
